UNITED STATES PATENT OFFICE.

WILLIAM LEE REYNOLDS, OF PROVIDENCE, RHODE ISLAND.

DESIGN FOR A GEM-SETTING.

SPECIFICATION forming part of Design No. 12,579, dated November 22, 1881.

Application filed October 13, 1881. Term of patent 3½ years.

To all whom it may concern:

Be it known that I, WILLIAM LEE REYNOLDS, of the city and county of Providence, and State of Rhode Island, have invented a new and useful Design for Gem-Settings; and I do hereby declare that the following specification, taken in connection with the accompanying drawings, forming a part of the same, is a full, clear, and exact description thereof.

10 My design consists in a gem-setting of circular contour, having a central opening for the reception of a brilliant or other stone, which opening is surrounded by an inwardly and downwardly beveled border, provided with a 15 diagonally knurled or beaded outer edge, the said border joining the side of the setting.

My design for a gem-setting is particularly adapted to those articles of jewelry known as "studs," "ear-drops," "scarf-pins," &c.

20 Referring to the drawings, Figures 1 and 2 represent face views of the setting, respect-

ively with and without a stone combined. Fig. 3 shows a side view of the same.

As shown in the several figures, the face of the setting is circular in contour, and is provided with a central opening, *a*. This opening is surrounded by a border, *b*, which is beveled inward and downward, as particularly shown in Fig. 3. At the outer edge, *d*, of the border—that is, at the junction of said border with the side *c* of the setting, which side may be at right angles to the face, or slightly inclined thereto—the setting is diagonally knurled or beaded, producing a neat and ornamental effect.

What I claim as my invention, and desire to secure by Letters Patent, is—

The design for a gem-setting, substantially as herein set forth.

WM. LEE REYNOLDS.
